UNITED STATES PATENT OFFICE.

ROBERT O. HOFFMAN, OF PENSACOLA, FLORIDA, ASSIGNOR OF ONE-THIRD TO ALEXANDER LISCHKOFF AND ONE-THIRD TO THOS. E. BIRD, BOTH OF PENSACOLA, FLORIDA.

CIGAR-VENDING MACHINE.

1,134,742.

Specification of Letters Patent.

Patented Apr. 6, 1915.

Application filed June 22, 1914. Serial No. 846,547.

To all whom it may concern:

Be it known that I, ROBERT O. HOFFMAN, a citizen of the United States, residing at Pensacola, in the county of Escambia and State of Florida, have invented a new and useful Cigar-Vending Machine; and I do hereby declare the following to be a full, clear, and exact description of the invention, such as will enable others skilled in the art 10 to which it appertains to make and use the same.

This invention relates to vending machines, and to an improved cigar vending machine in particular, and as an object of 15 the invention it is the aim to provide a machine of this nature comprising efficient and practical features of construction.

One of the features of the invention is the provision of a cylindrical drum having a 20 plurality of divisions for the reception of cigars, and provided with a ribbon extending about the drum over the divisions to hold the cigars therein, and having one end connected to the drum, and the other end 25 to a spring tensioned roll, in combination with a coin controlled mechanism including a pivoted lever adapted to be operated by a coin to operate the lever (which in turn contacts with a ratchet disk of the drum) to operate the drum intermittently by the action 30 of the spring roll to discharge a cigar.

In practical fields the details of construction may necessitate alterations, falling within the scope of what is claimed.

35 The invention comprises further features and combination of parts, as hereinafter set forth, shown in the drawings and claimed.

In the drawings:—Figure 1 is a view in 40 perspective of the improved cigar vending machine constructed in accordance with the invention. Fig. 2 is a vertical sectional view on line 2—2 of Fig. 1 just immediately adjacent one side of the casing, in order to 45 illustrate the coin slot and the coin controlling mechanism and the push plunger for operating said mechanism. Fig. 3 is a view similar to Fig. 2 showing the coin controlled mechanism as having been operated 50 by the reciprocating push plunger, and a cigar having been deposited in a cigar tray. Fig. 4 is a horizontal sectional view on line 4—4 of Fig. 2, not only showing the coin controlled mechanism in plan, but also show-

ing the spring tensioned roller to which the 55 ribbon of the drum is connected. Fig. 5 is an enlarged detail view showing the construction of the spring tensioned roller and the clamping means for the ribbon. Fig. 6 is a view in elevation of the idle roll over 60 which the ribbon passes. Fig. 7 is a detail view illustrating the connection between the ribbon and the drum. Fig. 8 is an enlarged detail view of a drum showing a plurality of divisions, in each one of which a package 65 of cigars may be arranged. Fig. 9 is a detail perspective view of the package of cigars.

Referring more particularly to the drawings 1 designates a casing having a suitable 70 base 2, and in the lower portion of which a suitable coin drawer or box 3 is arranged slidably. Mounted in bearings of the casing is a transverse shaft 4, on which a cylindrical drum 5 is mounted, and to one side 75 of the drum a ratchet disk 7 is secured as shown at 8. The teeth of the ratchet disk are designated by the numeral 9, and extend laterally of the disk. The drum on its periphery is provided with a plurality of 80 transversely disposed divisions 10, for the reception of cigars 11, each cigar having a paper covering or shield 12, in order to protect the same. These divisions are constructed by forming convolutions 11^a in a 85 sheet metal plate 12^a, which is secured at 13 to the end pieces 14 of the drum. Three or four of said convolutions are omitted, as shown at 14, thereby forming a blank space 15 in the sheet metal plate, to which an 90 arched plate 16 is secured, as shown at 17. One edge of the arch of said plate is provided with teeth 18. Mounted in bearings 95 of the casing is a rod 19, on which a roller 20 is loosely mounted between the collars 21. A coil spring 22 is also arranged on the rod 19 having one end connected to one side of the casing, and its other end connected to the roller 20, thereby spring-tensioning said roller. One end of the 100 roller 20 is constructed with a segmental extension 24, to which a lever clamp 25 is pivoted as shown at 26, and acting as a clamp for holding one end of a ribbon, band or tape 27 in a groove 28 of the roller. The 105 free end of the lever clamp is detachably secured to one end of the roller 20 by the thumb screw 29. The lever clamp 25 is con-

structed with an angular end 31 to engage over the beveled flange 32 of the roller, thereby more securely holding the lever clamp in said groove 28. The tape or band 27 passes over an idle roll 32 of the transverse rod 33, there being collars to prevent movement of the roller axially on the rod. The other end of the band, ribbon or tape is folded as shown at 34 and engages the teeth 18 of the plate 16, the folded portion of the tape being under the arch of said plate 16.

When the drum has all of its divisions filled with cigars, the tape or band extends completely about said drum, thereby holding the cigars in place, and owing to the roller 20 being spring tensioned, the drum is held against the action of said spring by the lever 36 pivoted at 37 to a ledge 38 of the interior of the casing. This lever 36 is provided with lateral portions 40 and 41 at its ends, each of which portions terminate in a beveled tooth 42. The tooth of the lateral portion 40 normally engages the teeth 25 at one side of the disk of the drum, so as to hold the drum with the ribbon or band wound thereabout against the action of the spring of the roller 20. This lever 36 is retained in such position by means of the spring 45 connected to the end of the lever having the lateral portion 41. A coin chute 46 is arranged in the casing having a coin entrance mouth 47 and a discharge end 48 terminating above the coin drawer or box 3. This coin chute 46 is provided with a transverse slot 50 extending into which is the nose 51 of the coin holding lateral projection 52, which is carried by the lever 36 adjacent the end having the lateral portion 41. The coin chute is also provided with an elongated cutaway portion 53. Mounted in a guide 54 upon the interior of one of the sides of the casing is a reciprocating push plunger 55, the tension of the leaf spring 56 of which holds the push plunger with its knob 58 protruding beyond the casing. The lower end of the push plunger is provided with a lateral arm 60, and when the push plunger is forced downwardly, and owing to the same being disposed angularly or inclined toward a coin slot, the lateral arm will engage the coin 62, which in turn pushes against the nose of said lateral projection, and operates the tooth of the lateral portion 41 of the lever portion 36 toward the ratchet teeth of the disk, thereby releasing the tooth of the lateral portion 40 from the teeth of the opposite side of the disk, which will permit the drum to partially rotate, owing to the action of the spring of the roller 20. Just so soon as the coin passes the nose of said lateral projection and drops into the coin box or drawer 3, the spring of the lever 36 throws the tooth 65 of the lateral portion 40 back in engage-

ment with the teeth of said disk, thereby preventing further movement of the drum, until another coin is dropped into said chute. The teeth of the disk of the drum are so arranged relative to the beveled teeth 70 of said lateral portions 40 and 41 of said lever 36, so that when a coin is substantially one-half past the nose of said lateral projection, the tooth of the lateral portion 41 will be in engagement with one of the teeth 75 of said disk, in which case the drum will have moved substantially one-half the distance between two of the teeth (adjacent the lateral portions 40) of the disk. As soon as the coin fully passes the nose of said lateral projection, the tooth of the lateral portion 41 disengages the tooth of the disk, and owing to the tension of the spring of the lever 36, the tooth of the portions 40 engages the next tooth of said disk, thereby 80 in this manner the drum makes a full partial revoluble movement and discharges a cigar through the opening 68 of the transparent hood 69 into the cigar tray 70 where it may be removed. The transparent hood 90 69 is hinged at 72, to the other portions of the hood 73, which is not transparent. A partition 74 extends downwardly toward the ledge 38, from where the transparent hood is hinged, thereby obscuring the coin 95 controlled mechanism from view. The transparent hood is provided with a suitable lock, as indicated at 75, whereas the drawer or box 3 is provided with a lock 76.

In Fig. 9 a package of cigars is illustrated 100 and designated by the numeral 77. The individual cigars of such packages may be used in each one of the divisions 10 of the drum, or as shown in Fig. 8, the divisions 105 may be filled with packages such as shown in Fig. 9.

Where the ribbon or tape or band is attached to the drum the word "Empty" is printed, and when this word reaches a location opposite the opening in the hood, it is 110 to be understood that all the cigars have been vended.

The invention having been set forth, what is claimed as new and useful is:—

A coin controlled escapement device comprising in combination with a ratchet disk, spring tensioned means therefor, a spring tensioned lever having a tooth at each end, one of said teeth of the lever being normally in engagement with the teeth of the ratchet disk to hold the same against the action of the spring tensioned means, a coin chute, a supporting frame to which said lever is pivoted, a projection carried by the lever and extending laterally and partially transversely of the coin chute, said frame having guides, a reciprocating spring tensioned plunger mounted in said guides and having its lower portion bent laterally, said plunger being arranged so that the lateral 120

bent portion thereof assumes a position normally upon the exterior of the chute, said plunger adapted to be reciprocated causing the bent portion to extend into the chute to engage the coin to push the same past the nose of the projection of said lever, thereby permitting the teeth of the lever to intermittently coöperate with the teeth of the disk to allow the disk to make a partial

revolute movement under the action of the 10 spring tensioned means.

In testimony whereof I have signed my name to this specification in the presence of two subscribing witnesses.

ROBERT O. HOFFMAN.
